(57) **CLAIM**

The ornamental design for an optical fiber inspection probe,
as shown and described.

DESCRIPTION

FIG. 1 is an oblique perspective view of an optical fiber
inspection probe showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan thereof.

The dashed line showing of structural lines is included for the
purpose of illustrating non-claimed subject matter and forms
no part of the claimed design.
